(57) **CLAIM**

The ornamental design for a portable light, as shown and described.

DESCRIPTION

FIG. 1 is a perspective view of a portable light showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof;

FIG. 9 is a perspective view thereof showing that a lighting module of the portable light in FIG. 8 starts to turn;

FIG. 10 is a perspective view thereof showing that the lighting module of the portable light in FIG. 9 further turns halfway; and,

FIG. 11 is a perspective view thereof showing that the lighting module of the portable light in FIG. 10 further turns over completely.

The broken lines shown represent unclaimed portions of the article and form no part of the claimed design.
